ROPE FASTENER

Harry A. Pearson, Wilmette, Ill.

Application January 21, 1954, Serial No. 405,437

2 Claims. (Cl. 24—128)

This invention relates to a rope fastener, and more particularly to a fastener for securing the permanently knotted end of a rope to a structure, vessel, vehicle, or the like without having to tie the rope in any manner.

This invention may be used for securing the mooring line of a boat to a dock, securing such a line to the boat itself, or attaching a clothesline to a clothespole, or similar purposes.

The disadvantages of having to secure the end of a line by tying it to a structure are obvious such as the time required for tying and untying, the necessity of using a special kind of knot in order to be assured of a reliable fastening, and the difficulty of untying the knot after any considerable stress has been put on it.

When the mooring line of a boat is involved, there is the additional disadvantage that attaching the line to a fixed mooring or structure such as a cleat or bollard will produce some strain in either the rope or the boat, or both, whenever the tossing or swaying motion of the boat causes it to jerk against the mooring.

This invention avoids all these difficulties and disadvantages, and provides a means for fastening a rope or other line which is quick, easy, and at the same time reliable and provides for a resilient connection.

The invention will be described in relation to the embodiments shown in the accompanying drawings. In the drawings:

Figure 1 is a side elevation of one embodiment of this invention;

Figure 2 is a sectional view of the same embodiment, taken along line 2—2 in Figure 1.

Figure 3 is a side elevation of another embodiment of this invention; and

Figure 4 is a plan view of the embodiment of Figure 3.

The rope fastener of Figure 1 comprises a single length of resilient wire of relatively high tensile strength and is provided with a knot holder portion 10 fashioned at one end of this length of wire. The general configuration of the knot holder of this embodiment can be seen by reading Figures 1 and 2 together.

The knot holder may of course be of any suitable shape, so long as it is large enough to hold the rope to be fastened, and at the same time small enough to prevent a knot permanently tied in the end of the rope from slipping through.

If desired, the knotted end of the rope may be provided with a washer or sleeve of some durable material to prevent wear on the knot, or the rope adjacent thereto, when stress is placed on the rope to pull it tightly against the knot holder.

As illustrated in Figures 1 and 2, the knot holder portion 10 is formed at the base of the device and consists of a U-shaped portion 10a extending laterally and slightly upwardly and of proper spacing to receive the rope for which the device is intended and prevent a knot thereon from slipping through the U. From the knot holding portion the wire extends upwardly in a conical coil 11 and at

2

the top is turned downwardly to provide an internal central post 16.

While the spring shown in Figure 1 is conical in shape it may of course be helical, elliptical in cross section, or if any other suitable design that would provide guide channels for the rope when it is wound around the rope fastener as described below.

The spacing between adjacent turns of coil spring 11 is approximately equal to the diameter of the rope which 10 is to be fastened. In a preferred embodiment, the spaces are somewhat less than the diameter of the rope. For reasons explained below, the spacing may be made small-est at the part of the coil nearest the knot holder.

The device is attached at its bottom to the dock, boat, 15 post, or other structure, vessel, vehicle, etc., to which the rope is to be fastened. Any suitable means of attaching the coil spring may be employed so long as it is strong enough. In Figures 1 and 2, the bottom of the coil is attached by a plurality of clips 12 and screws 13.

The bottom of core 16 may be fixed to the base plate or to the structure, vessel, vehicle, etc., to which the fastener is attached. However, in a preferred embodiment the bottom of the core is restrained only against trans-verse movement. For example, the bottom of core 16 20 may be positioned in cavity 17, as shown in Figure 1, so that it can move up or down but is substantially entirely restrained from movement in any direction transverse to its axis. The advantage to this is that when stress is placed on core 16 in a direction perpendicular to its axis, 25 the top of the core can bend in the direction of the stress and the bottom of the core is free to move up and down.

Another way of achieving this desirable flexibility in core 16 is by fixing only the bottom of the core and leav-ing the top unrestrained, as in the embodiment of Figures 30 3 and 4.

The flexibility of core 16 provides one of the advantages of this invention by minimizing the effect on the rope (and the boat, in case of a mooring line) of sudden jerks ap-plied to the rope.

The degree of flexibility of the core should be kept from being too large in any embodiment in which the knot holder is positioned at or near the bottom of coil 11—otherwise too much stress will be placed on the knot holder when the core bends in the direction of the pull 45 of the rope.

With a flexible coil and with knot holder 10 at or near the bottom of the coil, the rope fastener must be installed so that the knot holder is on the opposite side of the fastener from the direction of the greatest pull on 50 the rope. For example, when the rope fastener of this invention is used as a mooring device, knot holder 10 should be placed on the shore side of the dock. If knot holder 10 is placed on the water side of the dock, and if core 16 and coil spring 11 are too flexible, the top 55 part of the rope fastener may be bent so far in the di-rection of the water that the purchase of knot holder 10 on the knot could be somewhat loosened.

In the form of this invention illustrated in Figures 60 and 4, the knot holder portion is formed at the top of the device rather than at the bottom. In this modification a U-shaped knot holder portion 10 is fashioned at the top of the device by so forming the wire after which the wire is coiled down in a conical spiral 111 and at the bottom coil is brought upwardly through the center to 65 provide a center post 16, the upper end of which is bent outwardly over the top convolution of the coil.

In this form the bottom convolution 14 of the coil may be welded to a base plate 15 and the base plate may be attached to the desired structure by means of a plurality 70 of screws.

To use the rope fastener of this invention, the rope to be fastened is first placed in knot holder 10 and the

knotted end is pulled snugly against the holder. The length of rope adjacent the knotted end is then passed at least once, and preferably several times, around the core by passing it through the adjacent turns of the spring coil. The rope may then be released from the user's hand, and will remain firmly attached to the rope fastener until it is released by unwinding the rope.

Both the fastening and unfastening processes are obviously done very easily and very quickly.

It is only necessary to keep the knotted end of the rope tautly held against the knot holder, in order to insure proper operation of this rope fastener. For this purpose, the rope wrapped around the core is of course not required to provide enough friction to resist the pull upon the line exerted by the boat, the weight on the clothesline, or other stress upon the line. All that is necessary is that there be enough friction to keep the knot snugly engaged in knot holder.

In addition to the friction between the core and the rope wrapped around it, there are two other sources of tension which act upon the rope end to keep the knot snugly engaged in the holder. Obviously there is no problem when stress is placed upon the line, as this only tightens the rope about the core, and when the additional pressure is transmitted to the knotted end this tightens the engagement of the knot in the holder. If the rope is permitted to sag, however, the rope fastener of this invention also avoids permitting the rope to become so loosened that the knotted end can work its way out of knot holder 10.

One of the two sources of pressure that avoid such a loosening of the rope is the following:

Any loosening of the rope will first result in a sag in that part of the rope length which is within the coil spring. This sag will tend to keep the rope from working its way loose from the core. This in turn keeps the knot snug against the knot holder.

The second source of pressure is derived from the spacing of adjacent turns of the coil spring. The adjacent turns may be spaced apart just slightly less than the diameter of the rope to be fastened. The adjacent turns will then grasp the rope where it enters the space within the coil spring and also where it leaves that space. Even though the pressure thus exerted on the rope is very slight, it will be enough to avoid any loosening of the rope from the core when the line lies slack, and thus to avoid any loosening of the knot in knot holder 10.

It is to be noticed that the force exerted on the rope by the pressure of adjacent turns of the coil spring is of course not required to be so great as to resist the greatest tension on the rope when it is pulled taut, but rather simply to resist the slight force produced by the sagging weight of the line when it is slackened.

If desired, adjacent turns may be more closely spaced, as just described, at only one point. Ordinarily this point would be chosen to be the point where the rope enters the space within the coil after leaving the knot holder—which will generally be at that part of the coil spring nearest the knot holder.

As will be seen, the rope holder of this invention may be used on any line or rope, no matter of what material it is made, so long as it is flexible enough to be wound at least once around the core. This will of course be affected by the diameter of the core.

The diameter of the rope or line with which this rope fastener is usable may range between very wide limits.

The upper limit may be considerably greater than the spacing between adjacent turns of the coil spring because of the flexibility of the coil—so long as the knot holder is designed to take that large a rope or line. The lower limit may be considerably less than the spacing between turns of the coil, so long as the knot on the end of the rope or line is made large enough (or is supplemented by use of a washer that is large enough) that it will not slip through the knot holder.

It will be seen that a single rope fastener may be designed for use with a variety of sizes of rope or line. A preferred fastener of this kind has a coil spring with a large number of turns which have spacing between them ranging from quite small spacing at one end to quite large at the other.

The above detailed description of this invention is given for clearness of understanding only. No unnecessary limitations should be understood therefrom, as modifications will be obvious to those skilled in the art.

20 I claim:

1. A rope fastener for securing a rope having a knot formed therein, said fastener comprising: an arcuate knot-holding arm having an opening at least as large as said rope and of lesser size than the formed knot for restricting movement of the rope beyond the knot without necessitating tying the rope thereto, said opening of said arcuate knot-holding arm being U-shaped and capable of receiving a rope which is inserted laterally therein, a spirally wound flexible upstanding coil secured to said 25 knot-holding portion and extending in spaced relation thereto, said coil being adapted to receive and frictionally engage the rope beyond its formed knot when the rope passes through adjacent convolutions of said coil, said adjacent convolutions being spaced apart a distance not exceeding the diameter of the rope, an upstanding post extending substantially axially of and internally to said coil, said post being substantially centrally positioned in spaced relation to convolutions of the coil and being adapted to receive at least one turn of the rope, and a 30 base secured to one end of the coil to form a support means therefor, said fastener serving to securely retain a knotted rope without necessitating tying the rope to the fastener by the combined action of said knot-holding portion that prevents movement therethrough of the rope 35 beyond said knot, the said spirally wound coil frictionally engaging the rope when the rope passes through adjacent convolutions, and the said centrally positioned post that frictionally receives at least one turn of the rope wound thereon.
- 40 2. The rope fastener of claim 1 wherein said arcuate knot-holding arm is positioned at and secured to one end of said upstanding coil and said upstanding post is flexible.

- 50 3. The rope fastener of claim 1 wherein said arcuate knot-holding arm is positioned at and secured to one end of said upstanding coil and said upstanding post is flexible.
